UNITED STATES PATENT OFFICE.

CHARLES D. BONSAUL, OF NEW KENSINGTON, PENNSYLVANIA.

CARLINE REINFORCEMENT AND LOAD-LIFTING ARRANGEMENT.

Application filed March 17, 1926. Serial No. 95,425.

In some cars the roof structure comprises roof sheets spanning the distance between the opposite side plates with separate or integral carlines at the juncture of adjacent roof sheets. (Sometimes the adjacent margins of adjacent roof sheets are so formed and secured together as to perform the functions of the usual carline. These are called "integral carlines".) The bottoms of the carlines (integral or otherwise) are substantially flush with the lower surface of the roof sheets, making it impossible to secure a rope or chain to any part of the roof, therefore, it is difficult and cumbersome to move heavy 15 ladings into, out of or around in the car.

My invention resides in reinforcing all, or some of the carlines of an all metal car roof by means which also constitute a support for longitudinally extending beams, which beams 20 are used for attaching loading devices.

The beams extend longitudinally of the car and may span the distance between two adjacent carline reinforcements or three or more carlines or, in fact, may effectively extend 25 the full length of the car. The beams may be positioned in parallel pairs, as shown in Fig. 1, or in parallel pairs in combination with single beams, as shown in Fig. 2, or in 30 staggered relation, as shown in Fig. 3, or they may be positioned in alignment. Various arrangements and combinations of the carline reinforcements and beams may be devised to suit the requirements of the railroads and shippers.

An object of the invention is to provide 35 web plates to strengthen the carlines of a railway car and to provide beams to prevent these web plates from buckling which beams are below and spaced apart from the roof so as to furnish a place for attaching a loading device.

The invention reinforces the individual carlines to sustain vertical loads; obtains 45 cooperation between the adjacent carlines to sustain horizontal loads; reinforces the roof framing against distortion in a horizontal plane. The means connecting the adjacent carlines are also beams and provide a place to attach a block and tackle or rope to raise 50 the lading. These connecting means or beams extend longitudinally of the car so as to provide a large range of operation which is particularly advantageous if the lading is long, such as automobiles or rails; furthermore, the weight of the sustained lading is 55 distributed to at least two reinforced carlines.

The end plate is the end carline of a railway car for all intents and purposes of this invention, therefore, no distinction is made in the claims therein.

60

In the drawings:

Figs. 1, 2 and 3 are diagrams showing various arrangements of applying the device to a railway car.

Fig. 4 is a partial cross section of a roof 65 of a car with my device applied thereto.

Fig. 5 is a section on line 5—5 of Fig. 4.

Fig. 6 shows a modified construction.

In the drawings I have shown a so-called "all steel" metallic roof comprising a plurality of sheets 2 spanning the distance between the opposite side plates 3 of the car and secured thereto. Each sheet is provided with upstanding web portions 4 at its opposite sides, which portions are flanged (5) toward the adjacent roof sheets. These laterally extending flanges of adjacent sheets are secured together to form a substantial inverted channel, which section performs the usual functions of a carline. These inverted 70 channel sections are positioned above the roof sheets 2 and outside of the car so that they do not occupy any of the loading space within the car. The roof sheets are preferably formed from a rectangular plate and as 75 the inverted channel section decreases in depth toward the side of the car the laterally extending flange 5 is bent downwardly to overlap the web portion of the adjacent sheet, as shown in Fig. 4. At the eave of the 80 car this downwardly extending portion is bent to form a flange 6 which is secured to the side plate by such means as the rivet 7.

While I specifically describe one type of roof it is understood that my device may be applied to other types of car roofs.

While my device a vertically disposed web plate 8 is positioned to engage the web portion 4 of a roof sheet and its upper edge is flanged and secured to the laterally extending flanges 5 of the roof sheets by the same means (9) which secure the roof sheet flanges together. This plate is preferably horizontal along its lower edge (10) so as to obtain the maximum strength and greatest clearance between the roof sheets and the loading beams 11 without reducing the loading capacity of the car.

A companion plate 12 (integral or separate) may be used to provide a pair of vertically disposed plates, each engaging the web portion of the adjacent roof sheets and pref-

erably provided with upper flanges which are secured to the laterally extending flanges of the adjacent roof sheets. Each of the pair of plates has an outwardly projecting flange 13 at its lower edge, which flanges materially strengthen the plates, vertically and laterally, and also provide means for securing "ice tongs" to the plates. It is desirable to secure the bottom portions of these plates together to secure cooperation between them in resisting vertical or horizontal stresses. This may be accomplished by the use of a flat plate 14 secured to both of the outwardly projecting flanges 13 or by an inverted U-shaped member 15 secured to both of the webs and flanges of the plates 8-12. These plates also furnish means of attaching load lifting devices.

Leading beams 11 extending longitudinally of the car are positioned between the adjacent pairs of web plates and are located below the roof sheets and spaced therefrom so that ice tongs, differential chains or other lifting devices may be easily and removably attached thereto. These beams prevent the web plates from buckling under load, thereby securing co-operation between adjacent web plates.

The longitudinal loading beams may be made of pressed metal of any suitable configuration or may be made of a standard rolled section similar to that illustrated.

The accompanying drawings illustrate the preferred form of the invention, though it is to be understood that the invention is not limited to the exact details of construction shown and described, as it is obvious that various modifications thereof within the scope of the claims will occur to persons skilled in the art.

I claim:

1. In a railway car, the combination of metallic roof sheets having upstanding web portions with lateral flanges at their side margins, with the lateral flanges of adjacent sheets secured together, a vertically disposed plate engaging a web portion of a sheet and secured to the flange of said sheet, and a beam positioned on each side of said plate and secured thereto.

2. In a railway car, the combination of metallic roof sheets having upstanding web portions with lateral flanges at their side margins, with the lateral flanges of adjacent sheets secured together, a vertically disposed plate engaging a web portion of a sheet and secured to the flange of said sheet, and a beam positioned on each side of said plate and secured thereto, said beam being located below and spaced from said roof sheets.

3. In a railway car, the combination of metallic roof sheets having upstanding web portions with lateral flanges at their side margins, with the lateral flanges of adjacent sheets secured together, a pair of vertically disposed plates, each engaging a web portion

of adjacent sheets, and a beam positioned on each side of said plates and secured thereto.

4. In a railway car, the combination of metallic roof sheets having upstanding web portions with lateral flanges at their side margins, with the lateral flanges of adjacent sheets secured together, a pair of vertically disposed plates, each engaging a web portion of adjacent sheets, and a beam positioned on each side of said plates and secured thereto, said beam being located below and spaced from said roof sheets.

5. In a railway car, the combination of metallic roof sheets having upstanding web portions with lateral flanges at their side margins, with the lateral flanges of adjacent sheets secured together, a pair of vertically disposed plates, each engaging a web portion of adjacent sheets, a beam positioned on each side of said plates and secured thereto, and a member connecting the plates and beams together, said beams being located below and spaced from said roof sheets.

6. In a railway car, the combination of metallic roof sheets having upstanding web portions at their side margins and means to secure the adjacent sheet together, a pair of vertically disposed plates, each engaging a web portion of adjacent sheets, said plates having oppositely projecting flanges at their lower edges, and a beam extending normal to said pair of plates from each side thereof, said beams resting upon said flanges and secured thereto, said beams located below and spaced from said roof sheets.

7. In a railway car, the combination of metallic roof sheets having upstanding web portions at their side margins and means to secure the adjacent sheets together, a pair of vertically disposed plates, each engaging a web portion of adjacent sheets, said plates having oppositely projecting flanges at their lower edges, a beam extending normal to said pair of plates from each side thereof, said beams resting upon said flanges and secured thereto, said beams located below and spaced from said roof sheets, and a member positioned between said plates and secured to the flanges thereof.

8. In a railway car, the combination of metallic roof sheets having upstanding web portions at their side margins and means to secure the adjacent sheets together, a pair of vertically disposed spaced apart plates, each engaging a web portion of adjacent sheets, said plates having opposite projecting flanges at their lower edges, a beam extending normal to said pair of plates from each side thereof, said beams resting upon said flanges and secured thereto, said beams located below and spaced from said roof sheets, and a member positioned between said plate and secured to the flanges and webs thereof.

CHARLES D. BONSALL.
